UNITED STATES PATENT OFFICE.

WILLIAM BUNTING, JR., OF BROOKLYN, ASSIGNOR TO THE MEYER-SNIFFEN COMPANY, (LIMITED,) OF NEW YORK, N. Y.

MEANS FOR RAISING AND LOWERING VALVES.

SPECIFICATION forming part of Letters Patent No. 397,829, dated February 12, 1889.

Application filed August 15, 1888. Serial No. 282,806. (No model.)

To all whom it may concern:

Be it known that I, WILLIAM BUNTING, Jr., a citizen of the United States, and a resident of Brooklyn, in the county of Kings and State 5 of New York, have invented certain new and useful Means for Raising and Lowering Valves, of which the following is a specification.

Previous to my invention it has been common to provide a basin, sink, or bath-tub with a combined valve and overflow-pipe, and to provide means for lifting the same to permit the discharge of the contained water.

My invention has for objects to provide a 15 simple and easily-operated raising and lowering means by which the combined valve and overflow-pipe may be lifted to and held at any desired height within its range of movement, according as a quick or slow discharge is desired, and by which the same may be lowered to seat the valve proper without danger of dropping the contrivance and injuring the basin or other receptacle, or jarring and loosening the joints or seams thereof.

25 To these main ends my invention consists in the features of construction and combinations of parts hereinafter more fully described, and particularly pointed out in the appended claims.

30 In the accompanying drawings, Figure 1 is a central vertical section of a contrivance embodying my invention, and Fig. 2 is a horizontal section taken at the line $x-x$ of Fig. 1.

The same parts in both views will be found 35 designated by the same numerals of reference.

2 represents a portion of a set basin, bath-tub, or analogous structure; and 3, the slab or top rail thereof. The bottom of the fixture is formed with a discharge-opening, as usual, in 40 which is inserted a hollow screw-plug, 4, having a tapering valve-seat, 5. Cast within the bore of the plug is a strainer, 6, and a centrally-arranged upwardly-projecting socket, 7, for centering and guiding the valve and 45 overflow-pipe.

8 designates the valve proper, and 9 the stand or overflow pipe, both devices being made, preferably, of a single piece. A narrow bridge-piece, 10, is provided within the overflow-pipe, and has depending from it cen-

trally a stem or spindle, 11, which is fitted to slide within the socket 7 of the outlet-plug, and thus guide the valve in its movement to its seat. The upper end of the overflow-pipe is threaded to receive a threaded hollow cap-piece, 12, which is provided with a transverse bar, 13, preferably formed with an upward bend at its center.

14 designates a link or rod having a hook, 15, at its lower end to engage with the cross-bar 13 of the overflow-pipe, and having a threaded portion, 14, to engage a nut, 15^a, provided for preventing the uncoupling of the hook.

To the slab or rail or top 3 of the structure 65 is secured a vertically-mounted curved bracket or support, 16, terminating in a horizontal direction. This may be fixed in position in any desirable manner. In practice I provide the bracket with a screw-stem, 17, having a 70 square head or shoulder, 18, and make a square hole in the slab or top to prevent turning of the bracket, a nut, 19, being applied to the bolt or stem at its lower protruding end to hold the bracket down tight upon the slab or 75 top piece.

20 designates a shell having a horizontal tapering bore or opening for the accommodation of a tapering plug, 21, and a cylindrical bore for the reception of a split ring or spring-packing, 22. The smaller end of the plug is preferably formed with a threaded socket, 23, for the shank of a short retaining, compressing, and adjusting screw, 24. The shell or casing is cut away or slotted, as seen at 25, 80 and is provided with a handle portion, 26, and an outwardly and downwardly projecting arm, 27, the lower extremity of which is bifurcated for the reception of the upper end of the link 14. The forks of the arm 27 and the upper 90 end of the link 14 are perforated in line and connected together by a pin or screw, 28. Through the cut-away 25 in the shell extends horizontally from the bracket a threaded stud, 29, which is screwed into a threaded seat 95 formed in the plug 21. In practice the bracket is secured to the plug before being affixed to the top plate or slab.

At Fig. 1 the valve is shown as seated in full lines and as raised in dotted lines, the 100

broken line Y denoting the height to which the water will rise in the receptacle before overflowing into the stand-pipe and discharging.

5 In order to lift the combined valve and overflow-pipe from the full-line to the dotted-line position, the shell is turned (by means of the handle or the arm 27, or both) rearwardly upon the plug as a center or axis until the shoulder 30 strikes against the bracket, and in order to lower the valve and overflow-pipe the shell is moved in an opposite direction, all as plainly indicated by the drawings. The spindle 11 and socket 7 are made of such 15 length relatively to the lift of the valve that the latter will be always maintained in line with its seat. The spring 22 fits closely within the cylindrical bore of the shell with a pressure against the inner shoulder of the shell 20 and the back of the screw, and by the friction of the parts the gravity of the overflow-pipe and its connections is overcome. For this reason the valve may be raised to any extent within the limits of its movement and remain 25 suspended without keeping the hand employed, and without the use of catches of any kind.

Inasmuch as the friction of the parts at the center of movement of the shell is sufficient 30 to keep the overflow-valve suspended at any point, it will be understood that the same can never accidentally fall and damage the basin or tub or loosen or crack the joints or seams thereof.

35 If it be desired to remove the overflow-pipe at any time for cleaning purposes, the retaining-nut 15^a may be run up the rod or link and the hook detached from the cross-bar.

What I claim as new, and desire to secure 40 by Letters Patent, is—

1. The combination, with a combined over-

flow-pipe and valve, of the vertically-mounted bracket 16, terminating in a horizontal direction, the horizontal plug 21, arranged transversely of said bracket and connected thereto, 45 the shell or casing 20, mounted to turn on said plug, the arm 27 on said shell, and the link 14, as set forth.

2. The combination, with a combined overflow-pipe and valve, of the bracket 16, terminating in a horizontal direction, the horizontal plug 21, arranged transversely of said bracket and connected thereto, the shell or casing 20, having the cut-away 25 and mounted to turn on said plug, the arm 27 on said 55 shell, and the link 14, as set forth.

3. The combination, with a combined overflow-pipe and valve, of the bracket 16, terminating in a horizontal direction, the horizontal plug 21, arranged transversely of said 60 bracket and connected thereto, a shell or casing, 20, having the cut-away 25 and mounted to turn on said plug, a handle, 26, and an arm, 27, on said shell, and a link, 14, connected to the arm and to the overflow-valve, as set forth. 65

4. The combination, with a combined overflow-pipe and valve, of the bracket 16, terminating in a horizontal direction, the horizontal plug 21, arranged transversely of said bracket and connected thereto, a shell or casing, 70 20, having the cut-away 25 and mounted to turn on said plug, the arm 27, the link 14, and a frictional packing between said plug and shell to overcome the weight of the suspended parts, as set forth.

Signed at New York city, in the county of New York and State of New York, this 14th day of August, A. D. 1888.

WM. BUNTING, JR.
